RAIL ANCHOR

John William Skeel, North Girard, Pa., assignor
to True Temper Corporation, a corporation of
Ohio

Application June 8, 1946, Serial No. 675,495

18 Claims. (Cl. 238—329)

1

My invention relates to rail anchors and relates more particularly to a rail anchor of the general type employing a pair of relatively interlockable rail flange engaging parts.

More particularly, my present invention involves certain novel features of improvement in rail anchors of the general type disclosed in the prior patent to Cooper and Steadworthy No. 1,366,558 dated January 25, 1921, which are characterized by the provision of a U-shaped clamp member adapted to grip one side flange of a rail base and a spring member driven between a pair of clamping arms of said clamp member and engaged with the underlying web interconnecting said arms below the rail base, and having its free end snapped upwardly, as a result of such engagement, to engage the remote side edge of the other rail flange. Rail anchors in improved forms of the above type have gone into very extensive use.

An object of my present invention is to provide such a "Stead" type two-part rail anchor adapted to exert improved gripping action on said rail base to more securely anchor the rail against subsequent dislodgment or slipping of said anchor under the varying conditions of railway use to which, at times, rail anchors are subjected.

Other objectives of my present invention are:

To avoid dislodgment, or slippage, between the rail and the rail anchor, when in place, by the pounding effect of the rails against the underlying ballast during passage of heavy rapidly moving trains over the rails;

To provide an improved anchor which will not unduly subject the rail flange to damage, as a result of derailed locomotives or cars traversing laterally extending portions of said anchors;

To provide an improved anchor which is susceptible of ready and easy placement on a rail base but at the same time will strongly resist dislodgment under normal heavy use conditions;

To provide an improved rail anchor of the two-part type adapted to achieve the foregoing objects, wherein both anchor parts may be preliminarily assembled, transported to the point of application, and then applied to said rail base as a unitary rail anchor;

To provide an improved anchor of the aforesaid primary type but provided with a retaining drive-on bar of sturdy construction, and of unique form, to meet the demand for a most reliable, easily applied, tightly secured, two-piece anchor.

To provide an improved resilient retaining member for a rail anchor of the aforesaid type, said member and body being so cooperatively constructed during placement of the anchor upon a

2

rail base, and a relatively rigid rail gripping body, so cooperatively constructed as to avoid overdriving of the retainer member in placement of the anchor upon a rail base;

5 To provide an improved resilient retaining member for a rail anchor of the aforesaid type, said member and body being so cooperatively constructed during placement of the anchor upon a rail base, and a relatively rigid rail gripping body, so cooperatively constructed as to avoid objectionable reactive rebounding effects of the retaining member during the operation of driving the retaining member into locking engagement with a rail base flange.

10 15 Other objects of my invention and the invention itself will be apparent to those skilled in the art to which my invention appertains and including those skilled in railway maintenance, by reference to the accompanying drawings of two 20 embodiments of my invention, and to the accompanying specification describing the said embodiments.

In the drawings:

25 Fig. 1 is a side elevational view of a first embodiment of my invention as applied to a rail base, the rail being shown in transverse sectional view and with one of the arms of the rail gripping member being indicated as broken away to expose the parts otherwise hidden by the broken away 30 arm portion;

Fig. 2 is a side elevational view of the channel-shaped rail gripping member of the said embodiment;

35 Figs. 3 and 4 are front and rear elevational views of the gripping member;

Fig. 5 is a top plan view of the channel-gripping member of Figs. 2, 3 and 4;

40 Fig. 6 is a side elevational view of the two parts of the anchor, of said first embodiment, as preliminarily assembled together, ready for unitary transportation to the place of application of the two-piece anchor to a rear base bottom;

Fig. 7 is an end elevational view of the driving 45 rearmost end of the retaining bar of the foregoing figures;

Fig. 8 is a view duplicating in a larger view the showing of Fig. 1 together with an additional showing, in dotted lines, of the factory assembled anchor parts hand placed on a rail base flange 50 in position to be driven onto the rail base bottom.

Fig. 9 is a view of the nature of that of Fig. 1, but illustrating a second embodiment of my invention, which I now prefer.

Fig. 10 is a side elevational view of the retaining bar of the said second embodiment.

Fig. 11 is a top plan view of the bar of Fig. 10. Figs. 12 and 13 are respectively front elevational and rear elevational views of the clamp member of the said second embodiment.

Fig. 14 is a top end plan view of the clamp of Figs. 12 and 13.

Figs. 15, 16 and 17 are similar views, respectively illustrating three successive positions taken by the retaining bar with respect to the clamp bar, the aforesaid bar being shown in side elevation, then clamp member being also shown, but with the nearest arm of the clamp member indicated as cut away to illustrate the interiorly disposed bar and the inner surface of the remote clamp side arm.

Fig. 18 is a side elevational view of the completely preassembled rail anchor in the ultimate preassembled relative positions.

Fig. 19 is a section taken on the line 19—19 of Fig. 18.

Fig. 20 is a section taken on the line 20—20 of Fig. 15.

Referring to the drawings of Figs. 1 to 8 inclusive which illustrate a first embodiment of my invention, and in all of which like parts are designated by like reference characters, the rail anchor thereof may generally be characterized as being of the aforesaid patented two-piece type, and comprises two parts, which are adapted to be co-operatively interlocked on a rail base, the rail gripping clamp member 1 affording one part, being separately illustrated in Figs. 2 to 8 inclusive, and the other part being in the form of a retaining bar 2, said parts being illustrated in operative interlocked relation with the rail base in Fig. 1.

The clamp member 1, shown in Figs. 2, 3 and 4, is of generally U-section channel form, and comprises a part of upstanding arms 6 and 7, and a planular web 5, each arm being so inwardly notched proceeding from its forward edge as to provide the divergent rail gripping upper and lower jaws 3 and 4, adapted to flatwise engage the upper and lower border surfaces of the same rail base flange.

The web of the clamp channel extends in a direction which is normal or at right angles to the side arms 6 and 7, but the plane of the lower jaws 4 is disposed at an angle of 45° to the plane of the upper surface of the web 5 whereby, when the clamp member is operatively secured to a rail base flange with the jaws 3 and 4 embracing the top and bottom surfaces to said flange, said web 5 will be disposed at an angle of 45° to the plane of the rail base bottom which coincides to the plane of the lower jaws 4 in engagement therewith. The clamp 1 and retaining bar 2 may have rounded edges, as shown.

The clamp member 1, when in operative position on the rail base, will cause the plane of the upper surface of the web 5 to be forwardly and upwardly inclined with respect to said rail base bottom and a projection of said plane will preferably intersect the rail base bottom near its middle at a point *x* which is directly below the rail web 10'.

The construction of the clamp member 1, above described, is of particular importance in view of the improved type of retaining member 2, which is peculiarly adapted for cooperative operation in connection therewith for the purpose of reliably retaining the gripping member in gripping relation with one of the rail base flanges and at the same time affording sufficient abutment surfaces at the lowermost outer sides of the arms 6 and

7, either of which is adapted to abut against a rail supporting tie.

However, my present invention may be applied to variant structures where such an angularity between the intersecting planes of the rail base bottom and the web is varied but I prefer no greater variation than 5°, plus or minus.

As a further feature of improvement to facilitate factory pre-assembly of the anchor members 1 and 2, as later described, the upper portions of the channel arms 6 and 7 are preferably correspondingly inwardly offset, so that all upper end portions of the channel arms 6 and 7 are preferably correspondingly inwardly offset, whereby all upper end portions of said arms from a portion of their front edges which is located somewhat below the front terminus of the lower jaw surfaces 4, will be disposed more closely together than are portions below said zone 8, as best illustrated in Figs. 2, 3 and 4. At 8', Fig. 1, by shading lines, and in Figs. 6 and 8, by lines 8' parallel to the line 8, the width of the converging portions of the arms to provide such offsetting, is indicated, and the amount of offsetting is also well shown in Figs. 4 and 3.

The offsetting is accomplished by bending each said arm inwardly from below the zone 8, although relatively short portions 8' converge upwardly and inwardly, the portions of said arms both above and below said portions 8' are normally preferably substantially parallel, but with the relatively upper portions being relatively disposed closer together.

The purpose of positioning the relatively upper portions of the clamp arms 7 and 8 so that their inner surfaces are relatively less widely interspaced is to effect a resilient frictional clamping engagement of the side edges of the rearmost section of the retaining bar 2 between the inner surfaces of the upper clamp arm portions, in order to conveniently afford a preliminary factory assembly of the anchor parts 1 and 2 in a manner which will maintain said parts in desired relative positions during handling, shipment and distribution, as well as during the initial step of application to a rail base.

Such lateral frictional gripping of the retaining bar, upon the imposition of such driving force as is required to apply the anchor to the rail, will permit of such relative adjustment of the parts as is desirable during application of the anchor to the rail. The frictionally maintained preliminary assembly of the clamp and bar also will permit a ready separation of the parts should such separation for any reason be at any time desirable.

As another feature of improvement, the corners 4a adjacent the junction of the lower jaw surfaces 4 and the forward edges of the clamp arms, are similarly displaced inwardly by an inwardly directed bending operation during the manufacture of the clamp 1; when the bar and clamp is pre-assembled, the inwardly deflected tips 4a overlie the bar section 13b, thus cooperatively with the clamp web 5 preventing up-and-down displacement of the medial portion 13 of the bar 2.

The retaining bar 2, as best illustrated in Fig. 9, comprises relatively forwardly and rearwardly extending end sections, 11 and 12 respectively, each curvilinearly merged at their inner ends with a downwardly bowed interconnecting intermediate section 13 of substantially shallow V-form, and the oppositely extending end sections 11 and 12 being each preferably at least

nearly straight with the exception that the front straight section 17 merges at 17' with its terminal upturned hook portion 21. The rear section 12 provides a preferably flat driving end surface 11.

The two arms 13b and 13a, of the intermediate V-section of the retaining bar, are of preferably different lengths, the arm 13b being relatively shorter, and the forward bar section 17 is tilted upwardly from the region of its junction with the arm 13b.

The end bar portions 17 and 12, therefore, are preferably not disposed in precise longitudinal alignment. The upper surface of one of said end portions is slightly inclined with respect to the plane of the other and the formation of the complete bar, including the downwardly bowed intermediate section, is such that normally, when the bar 2 is not subjected to flexing stress, as shown in Fig. 6, where the anchor is shown apart from the rail, a forward projection y, of the plane of the upper surface of the rearmost end section 12 will intersect the upper surface of the foremost end section at a point z which is disposed medially between the junction of said front section with the intermediate section 13 and its juncture 17', with the rearmost portion of the terminal hook formation 21. The planes of said upper surface portions of said end sections may be within 5° of coincidence, although a slightly greater variance is permissible with attendant efficient results.

Preferably, the retaining bar 2 will be of about the same thickness as the channel-shaped clamp member with which it is to be associated but, preferably, the retaining member will be made of spring steel and, to provide it with a V-form intermediate section 13, the lower surface of the bar will partake somewhat of a convexly curvilinear longitudinal form which is most pronounced at the bottom of the V and, proceeding in both directions, the outer surfaces of the arms of the V become more nearly straight as the junctions with the relatively straight front and rear sections 17 and 12 are approached, and whereat such lower surfaces gradually achieve a concave longitudinal form in the regions of juncture with said end sections, as at 16 and 15, respectively.

The upper surfaces of the V-arms 13b and 13a may conveniently be of more nearly longitudinally straight form, and while the angle of divergence between the arms 13b and 13a may be varied, I preferably dispose said arms at an angle which is greater than a right angle and, preferably nearer to an angle of 100°.

The principal purpose of the slight divergence between the planes of the normally substantially straight upper surface portions of the bar sections 12 and 17, and of the making the forward arm 13b of the V-section shorter than the arm 13a thereof, is to assure that there will be clearance between the lower surface of the rail base and a considerable portion of the length of the upper surface portion of the bar section 17 which is disposed forwardly of the forward terminus of the arm 13b of the V-section 13, when the anchor is fully applied to the rail base, as shown in Fig. 1.

At the same time, the sections 17 and 12 are sufficiently nearly in longitudinal alignment to avoid unnecessary and undesirable resilient rebounding of the driven end 12 during application of the anchor to a rail base.

With the anchor fully assembled and applied to the rail base, as in Fig. 1, the portion 31 of the upper surface of the bar section 12 makes

flatwise engagement with the rail base, with the planes of the upper bar section 12 and of the lowermost clamp jaws 4 being substantially in co-incidence, and the bar section 12 thus supplementing the rail gripping action of the lower clamp jaws 4.

The operation of preliminarily assembling the two members 1 and 2 is best accomplished by introducing the rearmost end 14 of the straight

10 arm portion 12 of the retaining bar 2 to the space below the relatively directed corner portions 4a which form the lower jaws 4 to the front edge portions of the channel arms 6 and 7, and above the foremost end of the web 5, and then pushing

15 the rear end of said bar rearwardly between the arms 6 and 7 until the intermediate section 13 of the retaining bar 2 is completely embraced by the relatively widely spaced power portions of said clamp arms.

20 When the bar has been projected between the lowermost more widely spaced portions of the arms 6 and 7 being then disposed below the zone 8, the rear end of the bar 2, which, at this time, projects rearwardly from the clamp member, is

25 forcibly displaced upwardly and will fulcrum on the forward edge 5a of the clamp web 5 until the rear end portion 12 has its upper surface approximately brought into the plane of the clamping surfaces of the lower jaws 4, as illustrated in Fig. 6.

30 This last operation may be accomplished by a hammer or, in factory practice, will usually be accomplished through the instrumentality of a precisely operable power press which holds the

35 channel clamp immovable during the operation.

The rotation of the rear portion of the retaining bar 2 about the forward upper edge of the web 5 will cause the side edges of the bar 12 to progressively move first through the zone 8' and

40 then above the zone 8 where said side edges are compressively frictionally gripped between the inset upper portions of the side arms 6 and 7 of the clamp member and such upward movement

45 of the rear end of said bar will therefore be attended by a slight resilient spreading of said clamp side arms to accommodate the full width of the bar therebetween. Such spreading of the side arms will be insufficient to militate against the proper action of the clamp member during

50 application or use of the rail anchor.

The bar 2 will thereafter remain in assembled relation to the clamp 1 and will resist relative movement with respect to said clamp member even though the anchor during handling, ship-

55 ment and transportation to the place of application and the initial operation of placement on a rail base flange preliminary to final driving may receive some rather rough handling.

The inwardly directed tips 4a of the lower jaw

60 portions overlie the marginal sides of the underlying retaining bar which thus is trapped or caged between said tips and the underlying forward portion of the clamp web 5, thus affording a guide for placement of the retaining bar 2 and assuring a sufficient degree of permanence in the assembly of the anchor parts.

To apply the anchor to a rail base, the upper and lower jaws 3 and 4 are, by hand, partially pushed onto the upper and lower surfaces of one

70 of the laterally presented base flanges of a rail, but such hand placement is insufficient to advance the jaw surfaces inwardly of the rail base a distance nearly as great as that ultimately achieved by a subsequent driving operation.

75 The upper edge surface 20 of the upturned bar

hook 21, by such hand placement, will slidily engage the bottom of the rail base in the region generally indicated at 20.

The workman then directs driving blows upon the end surface 11 of the rearmost section 12 to completely apply the assembled anchor to operative clamping engagement with the rail base, as illustrated in Fig. 1.

Such driving will first accomplish a translatory forward movement of the bar 2 to slidily move the upper surface 20 of the hook 21 towards the adjacent rail edge and, at the same time, the forward portion of the upper surface of the clamp web 5 will be engaged by the upper forward portion 13b of the channel member web 5, and the cam portion 13a of the bar V-section will be moved in a forward and upward direction responsive to successive blows directed against the bar end 11, and the jaws 3 and 4 will further telescope over the associated rail base flange 16a.

During the driving of the bar 2, the camming effect of the clamp web 5 causes the intermediately disposed portions of the bar to become resiliently deflected upwardly towards the rail base, and therefore clamp-holding power is resiliently stored in the bar.

The relative movement of the parts is continued until the rail base flange 16a occupies such a position between the jaws 3 and 4, as illustrated in Fig. 1, while the recited camming effect of the clamp web 5 increases its upward pressure against the medial resilient portion of the lower surface of the bar 2, and the upper surface of the bar hook 21 will be slid along the bottom of the rail base until the hook has achieved a sufficiently forward position where, responsive to the stored spring pressure in the bar, said hook is caused to snap upwardly over the edge 30 of the rail base.

A portion only of the power stored in the spring bar 2 by the recited camming action is released when the hook end of the section 17 passes over the front edge corner of the rail base flange 16b, and the balance of said power is utilized in increasing the holding power of the anchor.

Actual tests involving the application of many rail anchors, of the embodiment herein described, on railroad rails have demonstrated that the anchor, herein illustrated and described, may be applied to a rail base with little effort and with great positiveness, and without objectionable rebounding resilient effects, which otherwise would have a tendency to cause the retaining element to rebound rearwardly at each driving blow.

Also, my rail anchors of the present invention when fully applied to the base of a rail are maintained in position on such rail base under operating conditions which, in the past, have been found so severe as to cause loosening of the better types of prior types of anchors from the rails.

Again, it has been found that a distinct advantage results from the fact that the lower surfaces of the web 5 and the rearmost edges of the channel arms are each relatively angularly disposed at approximately 45° to and at opposite sides of a vertical plane passing through the lowermost corner c of the clamp that up-and-down movements of the rails causing an impact of the lowermost rail anchor clamp portion against even frozen "high" ballast promotes no substantial unbalanced force tending to displace the lowermost portions of the channel, in either direction, in any manner tending to loosen the anchor from the rail base.

Also, it has been found that the two anchor parts are readily preassembled at the factory and

that such preliminary adjustment of the two assembled parts is maintained despite rough handling until the anchors are fully applied to a rail base.

5 Figs. 9, et seq. inclusive, illustrate a second and preferred embodiment of my invention which involves changes in the form of certain parts of both the clamp and retaining bar members, which further refine the operative features of the anchor of Figs. 1 to 9 inclusive, and are conducive to increased permanence of the assembly of clamp and bar as well as contributing to greater positiveness in the application of the anchor to a rail base and also insuring continued assembly of the 10 clamp and bar parts when the anchor is removed from a rail base, even after a long period of use thereon, so that the anchor parts remain relatively assembled for re-application to a rail base.

Among the more noticeable changes in form of 15 the preferred anchor, is the provision of a deeper substantially V-form intermediate portion of the retaining bar shown at 53, the provision of the localized, more inwardly protruding projecting portions 91 adjacent the rearmost edges of the 20 clamp channel arms 56 and 57, and a more pronounced inward deflection of the more forwardly disposed portions 54a of the lower jaws 58. The 25 nature and consequent advantages of the above changed features of construction will more clearly hereinafter appear, from the following description of the two anchor parts in which the bar 52 will first be described, and wherein finally the 30 advantages accruing by the changed formations will be explained.

35 While the retaining bar 52 is of the same general form as that shown at 2 for the first described embodiment, although it is shown with preferred straight edges, thus being of rectangular cross-section, throughout, the V-shaped portion thereof generally indicated in Fig. 10 at 63, whose arms are relatively diverged somewhat more than a right angle, as before, and whose longitudinal extent is indicated at A, is of increased depth and longitudinal extent, being initiated at 66, where the V-shaped section becomes 40 merged with the forward section 67 of the bar, which point of merger substantially coincides with the corresponding region of juncture 16 of 45 said first embodiment.

However, the lowermost portion of the V-section 50 shown at 63c is disposed, not only lower than, but at a point nearer the rear end 61 of the bar than is the similar lowermost part 13c indicated in Fig. 6; similarly the region of juncture 65 between the rear section 62 and the rearmost arm 63a of the V-section is disposed substantially correspondingly more rearwardly than the similar juncture 15 of the first embodiment shown in Fig. 6.

As indicated by the dotted line Y, and the 55 point Z of the upper surface of the bar section 61, and like the bar of the first embodiment, a projection of the plane Y of the upper surface of the rearmost bar portion 62 will intersect the upper surface of the foremost bar section 67 in a region which generally corresponds to the region z as determined by the dotted line y for the first embodiment as in Fig. 6.

It may be said that the bar 52, as illustrated in Fig. 10, is interchangeable with the bar 2 with 60 respect to cooperative association with the clamp 1 of the first embodiment, and because of the substantially greater length of the V-section 63b, said section affords a longer length of camming surface for engagement with the forward portion 65 of the surface of the clamp web 55.

The greater longitudinal extent of the inclined lower surface of the section 63b also effectively insures against such overdriving of the bar when placing the anchor upon a rail-base, as might otherwise sometimes accidentally occur should the lowermost surface 13c, Fig. 6 ride upwardly on the web 5 so as to engage the most forward edge of said web.

Although overdriving of the bar could seldom if ever be accomplished, were the bar of Fig. 10 employed in combination with the first described clamp 1 of Figs. 1 to 9, inclusive, this and other advantages are more efficaciously achieved when the bar 52 of Fig. 10 is employed in co-operative relation with the clamp 51 of the second embodiment, which will now be described and which is illustrated in Figs. 11 et seq.

The clamp 51, like the clamp 1, is cut from a strip of steel which may have, as shown, rounded side edges, and the web 55, and the jaw notches affording the upper and lower jaws 53 and 54 and end wall 94, are preferably similarly cut from the forward portions of the two arms 56 and 57 of the generally channel-shaped clamp, whose web is shown at 55.

However, whereas as shown in Fig. 5, the arms 6 and 7 are there shown as being initially non-converging in the fore and aft direction, the clamp of the present embodiment preferably provides arms whose upper portions, as shown in the top plan view of Fig. 14 converge from front to rear, whereby the rearmost portions are disposed substantially closer together, although the lowermost arm portions 92, are relatively preferably non-converging; in other words, the upper portions are relatively laterally skewed with respect to the lower portions of the same arms 56 and 57, whereby the rearmost inner surfaces of the arm portions which are disposed above the protuberances 91, become relatively more closely interspaced, than the other uppermost surface portions of said arms disposed forwardly thereof.

I also preferably slightly outwardly bow the arm portions 97 which are disposed below the dotted line 98, Fig. 18, in the up-and-down direction of the rearwardly extending bar arm section 62, to ensure lateral clearance for the V-form bar section and adjacent portions which in use of the anchor is disposed between said channel arm portions forwardly of the rearmost portions of said channel arms.

Such bowing contributes toward the desired result of avoiding constraining and frictional pressure engagement between the sides of said bar and inner wall surfaces of the clamp arms, in regions disposed forwardly of the most converged rearmost upper portions of the bar which by virtue of such convergence resiliently and frictionally grip a more rearward portion of the bar. From the fore-and-aft line 98, Fig. 18 the inner surfaces of the clamp arms 56 and 57, gradually converge slightly inwardly, in the upward direction through the narrow zone 105, such convergence terminating at the dotted line 98'.

The inward projections 58 and 91 are disposed at the two ends of the narrow zone, 105, of said inward convergence in the upward direction, as best shown in Figs. 19 and 20.

The surface of the lowermost jaw 54 is preferably disposed at the same angle of 45° relative to the plane of the web 55, as before, but portions of the arms of the channel are inwardly indentured somewhat differently. In the first place, the material of portions 54a of the arms

57 and 56, including the foremost portions of the lower jaws 54, is bent convergingly inward in the forward direction to a substantially greater extent than before, and the relatively 5 more widely spaced inner surfaces 92 of the forwardly disposed upwardly extending portions of said arms which are disposed between the inwardly bent portions 54a and the web 55, are of lesser upward extent than before, and where 10 the upwardly extending inner surfaces 92 merge with those of the inwardly bent portions 54a, more abrupt inclined shoulders 93 are produced by the bending.

At 91, the metal of the rearmost portions of 15 the arms is abruptly inwardly deflected to afford opposing inwardly directed protuberances.

The opposing protuberances 91 are preferably 20 relatively more closely interspaced at their rearmost portions but taper in more forward and downward portions for a relatively short distance until they merge with the adjacent inner surfaces of the zone channel walls, as shown in the top 25 elevational view of Fig. 14 and indicated by the abrupt indenturing depressions 81a visible in the side elevational view of Figs. 9 and 18.

The shoulder formation 93 below the forward 30 ends of the lower jaws 54 results largely from the indenturing of the outer surfaces of the clamp arms at 58.

The relative attitudes of the clamp and bar when, together, completely assembled onto a rail-base, are substantially the same as illustrated in Fig. 1, although the preferred deeper V-shaped section 13 extends more downwardly 35 within the clamp than before. The present embodiment affords a more permanent preassembly of the clamp and retaining bar, largely by virtue of the above recited differences of construction of the clamp and bar.

To effect a "factory" preassembly of the two anchor parts the rear section 62 of the retaining bar 52 is introduced through the forwardly 40 presented space above the web 55 and below the shoulders 93, being slid along the upper surface of the foremost upper corner of the web with the uppermost portion of the downwardly inclined outer surface of the arm 13a of the intermediate bar section 13, as illustrated in Fig. 8.

Then, the rearmost end 61 of the bar is manually 45 lowered to permit the surface 63a to slide along the foremost upper edge 55a of the web until the upper inner surface 100 of the bar section 63b is obstructedly engaged by the downwardly facing shoulder 93 at the forward edge of the clamp, whereupon the bar surface 31 is 50 manually lowered by tilting the forward portion 67 of the bar upwardly as shown in Fig. 16; the rear end of the bar is then elevated as shown in Fig. 17 until the rear bar section engages the 55 lower surfaces of the protuberances 91.

With the bar pushed rearwardly in such last 60 described inclined attitude until the upper surface 101 of the bar section 63b engages the shoulder 93, the assembly is subjected to a press operation 65 which forces the side edges of the rear bar portion 62 between the protuberances 91 of the clamp arms, the pressure applied being sufficient to cause the interposed bar portion to wedgingly spread the clamp arms sufficiently apart to permit the bar to pass between said protuberances to the ultimate preadjusted position illustrated in Fig. 18.

In such a preadjusted position the region of merger 66 between the bar portions 63b and 67 will be disposed closely adjacent to the forward

upper edge corner 103 of the clamp web. In such position the rear portion 62 of the bar 2 is tightly wedged at 104 between the rearmost converged portions of the clamp arms 56 and 57 in a region which is disposed adjacent to and above the protuberances 91. The bar portion 66 is prevented from upward or downward movement by engagement of its upper and lower sides, respectively, with the clamp shoulders 93 and the web edge 55a and the rear portion of the bar, in addition to the resilient, frictional, lateral clamping engagement by the clamp sides, is restrained from downward movement by reason of the presence of the obstructing protuberances 91.

The rail anchor as thus constructed and pre-assembled is now ready for packing, shipment, transportation to the railroad site of application to a rail-base, and application of such anchor is accomplished in the same manner as previously described for the first embodiment.

The presence of the underlying protuberances 91 effectively prevents the rear end portion 62 of the anchor from being deflected downwardly, either through rough handling before, or during application to a rail-base, and thus during forward driving the bar 52 can never approach such a more parallel position with respect to the clamp web, that by forward driving movement the bar could be so overdriven as to cause the mid-portion 63c to ride up the web edge 55a, or to achieve any attitude wherein the retaining hook 71 at the forward terminal of the bar could be projected beyond the remote rail-base flange edge.

On the contrary, during driving of the anchor onto the rail by blows against its rear end 61, the bar will move forwardly tending to effect substantial parallelism as between the lowermost surface of the portion 13b and the web 55 of the clamp, and thence upon continued driving the camming engagement between said web and bar surface will, while the hook 21 is driven forwardly in compressed sliding engagement with the bottom of the rail-base until the assembled anchor is completely applied to the rail-base with the inner facing surface of the hook 21 engaged with the remote edge of said rail-base and preventing displacement of the anchor from the rail-base in the well-known manner. As previously stated, during driving of bar 11 the pulling effort of the V-section 13b on the forward portion of the web 55 effectually telescopes the jaws 53 and 54 onto the rail base flange.

An advantage of the construction of the said last described preferred embodiment resides in the fact that the anchor thereof may be removed from a rail-base by downwardly directing blows upon the upper surface of the hook 21 to loosen the anchor from said base and importantly, such removal is without effect in impairing the necessary preassembled relationship of the clamp and retaining bar, which do not become separated, but remain in proper assembled relationship.

The rear portion 62 of the bar, is prevented by the protuberances 91 from being lowered and thereby the bar and clamp are maintained in the efficient, desired relative attitudes for re-application to a rail-base flange. Such desirable maintenance of the preassembled relation between the anchor parts is also contributed to by the caging formation at the forward lower portions of the clamp comprising the web 55, the shoulders 93 with the interposed more widely interspaced clamp arm portions 92, which similarly prevent

improper up-and-down dislodgment of the portion of the retaining bar which projects between said caging portions of the claim.

Having described my invention in two different embodiments, the first representing a preliminary, commercially advantageous and proved, form of my invention, and the second representing a further improvement, more perfectly insuring against deleterious results caused by improper or accidental handling or operation either before or after application of the anchor to a rail-base, and also insuring the retention of the two parts in proper preassembled relationship ready for re-application, I am aware that my invention may be embodied in anchor structures involving the principle of my invention, and within the scope of the appended claims.

I claim:

- 20 1. A two-piece rail anchor comprising a rail flange gripping clamp of the channel-shaped type having a pair of parallel upstanding arms each notched in its forward edge to afford a pair of relatively superposed clamp jaws adapted to fittingly embrace a rail base flange and said clamp adapted when affixed to said rail flange to dispose its web at an approximately 45° angle to the bottom of the rail base, and a retaining bar having substantially oppositely extending front and rear portions adapted for projection from between the arms of the clamp and terminating forwardly in an upturned hook, and the straight rear portion projecting rearwardly beyond the rear edges of the clamp arms and affording a rear end impact driving surface, said bar having a medial downwardly projected section adapted responsive to flow directed against said impact surface to make camming engagement with the upper surface of the clamp web to upwardly resiliently stress intermediate portions of the bar disposed forwardly of its said rear portion, to cause said hook to be snapped over the edge of the remote rail base flange, and the vertical extent of said medial section being substantially greater than the vertical distance between the most forwardly and most upwardly disposed forward edge portion of the web and the superposed lower surface of the rail base, when said clamp jaws are fitted onto the rail base flange.
- 40 2. A rail anchor comprising a rail flange gripping clamp of the channel-shaped type having a pair of parallel upstanding arms each notched in its forward edge to afford a pair of relatively superposed clamp jaws adapted to fittingly embrace a rail base flange and said clamp adapted when affixed to said rail flange to dispose its web at an approximately 45° angle to the bottom of the rail base, and a retaining bar provided with a pair of generally straight front and rear end portions, said bar adapted to have a major portion of said rear portion disposed between the arms of the clamp with its rearmost end projected rearwardly from said clamp to afford an impact driving surface, said bar terminating forwardly in an upturned hook and being medially bent to afford a substantially transversely channel-shaped medial bar section having a substantially forward upwardly inclined surface adapted for camming engagement with the upper forward surface portions of the clamp web to upwardly transversely relatively stress the intermediate portions of the bar to cause said hook to be snapped over the remote edge 75 of the rail base, and the vertical extent of said

medial section being substantially greater than the vertical distance between the most forwardly and most upwardly disposed forward edge portion of the web and the superposed lower surface of the rail base, when said clamp jaws are fitted onto the rail base flange.

3. A rail anchor of the two-piece type having a substantially U-shaped clamp provided with parallel arms, each correspondingly notched to provide a pair of upper and lower jaws for gripping one flange of a rail base, and provided with a lowermost web disposed in a plane normal to said arms, the planes of said clamp web and of said lower jaw surfaces converging forwardly at approximately a 45° angle, and a retaining bar having front and rear substantially straight sections respectively provided with a foremost upturned hook and a rearmost driving end, said bar comprising a medial section, of transversely channel-shaped form interconnecting the aforesaid sections and affording a forwardly, upwardly inclined lower cam surface, said bar adapted to have most of its rear section disposed between the arms of the clamp and its rear end projecting rearwardly therefrom, and said cam surface engageable with said clamp web responsive to forward driving of said bar by blows directed against said rear and to resiliently upwardly bend the intermediate portions of the bar to effect snapping of said hook over the remote base flange edge, and the vertical extent of said medial section being substantially greater than the vertical distance between the most forwardly and most upwardly disposed forward edge portion of the web and the superposed lower surface of the rail base, when said clamp jaws are fitted onto the rail base flange.

4. A rail anchor comprising a channel shaped clamp having jaw notches extending inwardly and towards the free end rear corners of both arms from the forward edges thereof to provide a set of upper and lower jaws adapted to embrace edge portions of the same rail base flange, the web thereof extending in convergent relation to the lower jaw surfaces at an angle of approximately 45°, and a retaining bar bent from initial straight form to afford an approximately medial section deflected substantially downwardly with respect to the other portions of the bar, so as to make it of substantially transversely channel-shaped form, said bar terminating forwardly in an upturned hook and adapted to be driven forwardly by blows directed against its rear end, said rear end extending rearwardly from between the clamp arms, said central portion adapted for camming engagement with the upper surface of the clamp web responsive to driving of the bar, and the intermediate portions of the bar comprising said central portion adapted to be resiliently bent towards the rail base bottom responsive to the resultant upward camming of the intermediate bar portion, to cause said hook to be snapped over the edge of the other rail base flange, and the vertical extent of said medial section being substantially greater than the vertical distance between the most forwardly and most upwardly disposed forward edge portion of the web and the superposed lower surface of the rail base, when said clamp jaws are fitted onto the rail base flange.

5. A two-piece rail anchor comprising a channel-shaped rail flange gripping clamp having a pair of upstanding clamp arms, so correspondingly notched as to afford corresponding pairs of upper and lower rail base flange gripping jaws so

directed that when said clamp is affixed to a rail flange with the lower jaws in flatwise engagement with the bottom of the rail base the web of said clamp will be disposed below the rail base in convergent relation to the mid-portion of the rail base bottom at an approximately 45° angle, and a retaining bar having a substantially straight rear section mostly disposed between the arms of the clamp and a rear impact driving end surface projected rearwardly from between said arms, with its rearmost end projected outwardly thereof, a substantially straight upwardly inclined front section of transversely channel-shaped form having a lower forwardly and upwardly extending cam follower surface terminating forwardly in an upturned hook, and a medial downwardly bent section interposed between and interconnecting said front and rear sections adapted for camming engagement with the upper surface of the clamp web when said bar is driven forwardly by blows directed against its said rear end, to resiliently deflect the front portion of said bar to cause said hook to be moved to and snapped over the edge of the remote rail base flange, and the vertical extent of said medial section being substantially greater than the vertical distance between the most forwardly and most upwardly disposed forward edge portion of the web and the superposed lower surface of the rail base, when said clamp jaws are fitted onto the rail base flange.

6. A two-piece rail anchor comprising a rail base flange gripping clamp of the type, having a pair of upstanding clamp arms, each clamp arm correspondingly notched to provide a pair of upper and lower rail flange gripping jaws so directed that when said clamp is affixed to a rail flange the web of said clamp will be disposed below the rail base in convergent relation to a medial portion of the rail base bottom at an approximately 45° angle, and a retaining bar provided with generally front and rear straight end portions both oppositely directed slightly upwardly, a portion of said rear end portion being disposed between the arms of the clamp and being in engagement with the bottom surface of said rail base, with its rearmost end extending rearwardly from between said arms, and said bar terminating forwardly in an upturned hook, said bar being medially bent to afford a substantially downwardly deflected medial section of substantially transversely channel-shaped form, said medial section having a lower relatively forward cam follower surface portion adapted for camming engagement with the upper surface of the clamp web to upwardly transversely stress the intermediate portions of the bar when said bar is driven by blows directed against its said rear end to cause said hook to be snapped over the edge of the remote rail base flange, and the vertical extent of said medial section being substantially greater than the vertical distance between the most forwardly and most upwardly disposed forward edge portion of the web and the superposed lower surface of the rail base when said clamp jaws are fitted onto the rail base flange.

7. A two-piece rail anchor, one piece thereof being generally in the form of a channel shaped clamp affording a pendant web and an upwardly extending pair of supporting arms, and the other piece being a retaining bar, said bar comprising a pair of oppositely extending end sections, and a relatively pendant interconnecting medial

75 section, the front end section terminating for-

wardly in an upturned hook formation, and the rear end section affording an impact driving surface at its rearmost end, said medial section being of the form of a transverse channel, said bar being normally so formed as to provide a spring portion, comprising said medial section and most of said front section, whose upper surface is interspaced below the plane of its extremities, the arms of said clamp being so inwardly notched proceeding from their corresponding forward intermediate edges to provide like upper and lower rail flange embracing jaws, with the lower jaw surfaces disposed in a plane disposed at a 45° angle to the relatively downwardly disposed clamp web, and adapted for flatwise engagement with the lower surface of said rail flange, said medial portion of said bar being initially disposable in the space between the rail base and clamp web and between the clamp arms, and said bar adapted to be moved forwardly when driven by blows directed upon its said impact surface, to concurrently effect camming engagement of said medial portion with the upwardly inclined clamp web, to advance the bar hook while engaged with the bottom surface of the rail base towards the opposite edge of the rail base, to resiliently upwardly deflect the said spring portion of the bar, and to tractively advance the clamp jaws further onto the clamped rail base flange, until said hook is snapped over the edge of the remote rail base flange.

8. A two-piece type rail anchor comprising a channel shaped clamp element having companion jaw notches for embracing a rail base flange, and extending rearwardly from the forward edges of the channel arms, with the planes of the lower jaw surfaces and the channel web relatively disposed at any angle between 40° and 50°, a spring retaining bar having substantially straight oppositely extending front and rear sections and a medial section, said rear and medial sections mainly disposable between the arms of the channel, said front section terminating forwardly in an upturned hook and said rear section extending rearwardly from between the channel arms to afford by its rear end an impact driving surface said medial section being of generally V-form and affording a forwardly and downwardly facing inclined lower surface adapted to make camming engagement with the correspondingly inclined clamp web, said front section extending forwardly and upwardly from its juncture with the upper end of the front arm of said medial section to dispose at least a major portion of the length of the upper surface of said front section adjoining said medial section substantially below a forward projection of the plane of the upper surface of said rear section, said bar adapted to receive driving blows directed against its said rear end to force said hook forwardly along the bottom of the rail, and said clamp web responsive to such driving of the bar adapted to cammingly direct the medial section upwardly and forwardly towards the rail base bottom, whereby said hook is snapped over the remote rail flange edge, said clamp jaws are concurrently tractively drawn by said medial section and channel web further onto the engaged rail base flange, said bar effecting resilient reactive pressure against said inclined clamp web and the said rail base surfaces engaged by the bar and clamp, to maintain said clamp, bar, and rail base in relatively interlocked relation.

9. A rail anchor comprising a channel shaped

clamp having jaw notches extending inwardly and upwardly from the forward edges of the clamp arms to provide a set of companion upper and lower jaws cooperatively adapted to embrace the same rail base flange, the web thereof extending in forward convergent relation to the lower jaw surfaces at an angle of approximately 45°, and a retaining bar having oppositely directed end sections, and a relatively interconnecting medial section of substantially V-form, the front arm thereof being shortest, said front section being inclined slightly upwardly and terminating forwardly in an upturned hook and the rear section terminating in a rearmost impact end portion, said rear section mainly disposed between the arms of the clamp and its impact end projected rearwardly beyond the clamp, said medial section adapted, responsive to forward driving of the bar, to cammingly engage the upper surface of said clamp web and to be upwardly deflected thereby, to apply upwardly directed stress upon the front bar section to cause its hook end to engage the rail base bottom and its more rearward portions to be resiliently bent toward the rail base bottom and to slidingly advance the bar hook along the rail base bottom to cause said hook to be snapped over the edge of the remote rail base flange, and said clamp arms being provided with two pairs of companion inwardly extending ledges, the first pair being faced downwardly and disposed below the forward portion of the lower jaws, and the second pair being faced upwardly and disposed relatively rearwardly and upwardly therefrom, and below a rearward projection of the plane of said lower jaws, said pairs of ledges being disposed respectively above and below respectively more forwardly and rearwardly disposed portions of the bar embraced by said clamp arms.

10. A two-piece rail anchor, one piece thereof being generally in the form of a channel shaped clamp and the other piece a retaining bar, said bar terminating forwardly in an upturned hook and comprising a pair of oppositely extending substantially straight sections and an interposed relatively interconnecting downwardly bowed section, said front section extending slightly upwardly from its junction with the intermediate section, the arms of said clamp being so notched as to substantially flatwise embrace the upper and lower border surfaces of a rail base flange in such manner as to dispose the intermediate web in a plane having an inclination of approximately 45° from the plane of the lowermost jaw surfaces, whereby when said bar is disposed between the clamp arms, and driven by its rear end transversely of the rail said bowed portion is adapted to effect camming engagement with the upwardly inclined clamp web to raise and advance the bar hook to cause it to make sliding engagement with the rail base bottom and to move it forwardly towards the opposite edge of the rail base until it is snapped over the edge of the remote base flange, also, to effect resilient upward deflection of the front bar section and to tractively advance the clamp jaws on the clamped rail base flange, both arms of said clamp in the region below and adjacent to the junction of the surfaces of the lowermost jaws and the front arm edges being provided with inwardly and downwardly directed shoulders to substantially effect caging of the portions of the bar disposable in the space defined by said shoulders and said clamp web to prevent "over-

driving" of the bowed bar portion forwardly through said space.

11. A two-piece rail anchor comprising a channel shaped clamp, and a retaining bar so formed as to afford a pair of oppositely extending generally straight end sections and a relatively interconnecting intermediate section of substantially V-form, said bar terminating forwardly in an upturned hook and rearwardly in an impact driving surface, both clamp arms being correspondingly so notched as to provide upper and lower jaws adapted to flatwise embrace the upper and lower border surfaces of a rail base flange in such manner as to dispose the intermediate web in a plane having an upward forward inclination of between 40° and 50° from the plane of the lowermost jaw surfaces, the intermediate bar section adapted, when the bar is driven between the clamp arms transversely of the rail, to be cammed upwardly by engagement with said inclined clamp web to advance the bar hook towards, and to be snapped upwardly over, the edge of the opposite rail base flange, to resiliently upwardly deflect the intermediate portions of the bar, and to tractively advance the clamp jaws on the clamped rail base flange, a relatively upper portion of the channel arms being skewed to dispose their inner surfaces adjacent their rear edges in more closely converged relation than the other more forwardly disposed portions thereof whereby to resiliently grip substantially localized portions of the sides of said bar rear section near its rear end, and each of said clamp arms in the region of said converged surfaces and below the position of the gripped bar portion being provided with inwardly directed shoulders adapted to afford companion ledges to prevent downward displacement of said gripped rear bar section.

12. A two-piece rail anchor comprising a channel shaped clamp, comprising a pair of upwardly extending interspaced arms and a pendant transverse web, and a retaining bar so formed as to afford a pair of oppositely extending generally straight front and rear sections and a relatively interconnecting medial section of substantially V-form, said bar terminating forwardly in an upturned hook and rearwardly in an impact driving end, both clamp arms being correspondingly so notched as to provide like pairs of companion upper and lower jaws adapted to embrace the upper and lower border surfaces of a rail base flange, the lower jaw surfaces and the upper surface of the channel web being relatively disposed at a forwardly converging angle of between 40 degrees and 50 degrees, the rear and medial bar sections being mostly disposed between the clamp arms with said driving end projected rearwardly of the clamp, and the forward arm of said V-form medial section adapted, when said jaws are partially positioned on said base flange and the bar is driven between the clamp arms transversely of the rail, to be cammed upwardly and to make tractive engagement with said inclined clamp web to cause the bar hook to be advanced toward the opposite base flange edge to cause upward deflection of the intermediate portions of the bar, and to tractively further advance of the clamp jaws onto the engaged rail base flange, said V-form section being joined to the rearmost portion of the front bar section at a lower level than the plane of the foremost portion of the upper surface of said rear section, whereby to provide a substantial gap between the rail base bottom and the

more rearwardly disposed upper surface portions of said forward section.

13. A two-piece rail anchor comprising a channel shaped clamp, and a retaining bar so formed as to afford a pair of oppositely extending generally straight end sections and a relatively interconnecting intermediate section of substantially V-form, said bar terminating forwardly in an upturned hook and rearwardly in an impact driving surface, both clamp arms being correspondingly so notched as to provide upper and lower jaws adapted to flat wise embrace the upper and lower border surfaces of a rail base flange in such manner as to dispose the intermediate web in a plane having an upward forward inclination of between 40° and 50° from the plane of the lowermost jaw surfaces, the intermediate bar section adapted, when the bar is driven between the clamp arms transversely of the rail, to be cammed upwardly by engagement with said inclined clamp web, to advance the bar hook towards and to be snapped upwardly over the edge of the opposite rail base flange, to resiliently upwardly deflect the intermediate portions of the bar, and to tractively advance the clamp jaws on the clamped rail base flange, said V-form section being joined to the rearmost portion of the front bar section at a lower lever than the region of juncture thereof with the foremost portion of the rear bar section and said front section being inclined upwardly from its junction with said V-form section, whereby to initially afford a substantial gap between the rail base bottom and the more rearwardly disposed upper surface portions of said forward section.

14. A two-piece rail anchor comprising a channel shaped clamp, and a retaining bar so formed as to afford a pair of oppositely extending generally straight end sections and a relatively interconnecting intermediate section of substantially V-form, said bar terminating forwardly in an upturned hook and rearwardly in an impact driving surface, both clamp arms being correspondingly so notched as to provide upper and lower jaws adapted to flatwise embrace the upper and lower border surfaces of a rail base flange in such manner as to dispose the intermediate web in a plane having an upward forward inclination of between 40° and 50° from the plane of the lowermost jaw surfaces, the intermediate bar section adapted, when the bar is driven between the clamp arms transversely of the rail, to be cammed upwardly by engagement with said inclined clamp web to advance the bar hook towards and to be snapped upwardly over the edge of the opposite rail base flange, to resiliently upwardly deflect the intermediate portions of the bar, and to tractively advance the clamp jaws on the clamped rail base flange, a relatively upper portion of the channel arms being skewed to dispose their inner surfaces which are adjacent their rear edges in more closely converged relation than the other more forwardly disposed portions thereof whereby to resiliently grip substantially localized portions of the sides of said bar rear section near its rear end, each of said clamp arms in the region of said converged surfaces and below the position of the gripped bar portion being provided with inwardly directed shoulders adapted to afford companion ledges to prevent downward displacement of said gripped rear bar section, and each of said clamp arms, in the region of the junction of said lower jaw surfaces with the relatively lower front edge surfaces of the clamp arms, being provided with inwardly directed shoulders

19

adapted to afford downwardly facing companion ledges adapted to restrict relatively upward movement of the portion of the bar disposed between said arm portions and between said ledges and the forwardly disposed portion of the upper surface of said channel web.

15. A unitary rail anchor comprising the combination with a channel shaped clamp element having a pair of upstanding arms, each of said arms having its forward edges so notched as to afford a pair of upper and lower jaw surfaces and said clamp being characterised by the channel web being disposed at approximately a 45° forwardly converging angle to the lower jaw surfaces, and by the arms thereof below the forward portion of the lower jaw surfaces being provided with inwardly extending downwardly facing companion ledges, and a more rearward and upward portion of said arms disposed somewhat below the plane of the lower jaw surfaces being provided with upwardly facing relatively front and rear companion ledges, of a retaining bar having substantially straight front and rear sections and a transversely trough-shaped intermediate section merged at its upper ends with said front and rear sections, said forward section terminating in an upturned hook, said bar adapted to be pre-assembled with said clamp with the rear bar section disposed between the clamp arms and projecting rearwardly therefrom, and having a portion overlying the rearmost companion ledges, and a more forward portion of the bar in the region comprising the juncture of said front and intermediate sections being substantially caged between the forward companion ledges and the channel web, the forward surface of the intermediate section being cammingly engageable with the upper surface of said web, and said anchor being adapted to be driven as a unit by blows directed upon the end of its rear section to cause its upper and lower jaws to embrace one rail base flange and to cause said intermediate section to be cammingly advanced on said web to snap said hook over the edge of the remote rail base flange, and the depth of said trough-shaped section being so great as to prevent its lowermost surface from being driven forwardly so far as to reach the restricted vertical space between the foremost upper edge of the web and the rail base surface disposed above said web edge.

16. The rail anchor substantially as set forth in claim 15, characterized by bar being of substantially uniform width, and the inner surfaces of the clamp arms, which are disposed in the

20

general region of outward projection of the rear end of the rear bar section from between said arms, being normally so closely interspaced as to resiliently compressively frictionally grip the side edges of the bar when operatively disposed therebetween, and the more forwardly disposed side edge portions of said bar being free of compressive engagement by said clamp arms.

17. The rail anchor substantially as set forth in claim 5, characterized by bar being of substantially uniform width, and a relatively upper portion of the channel arms being skewed to dispose their inner surface portions which are disposed in the region of the rear edges of the arms, in more closely converged relation than the other more forwardly disposed portions thereof, to effect resilient pressure engagement of said converged inner surfaces against the opposing sides of the bar portion interposed therebetween, and each of said clamp arms below the position of said bar portion being provided with inwardly directed upwardly presented companion ledges, said ledges adapted to restrain said gripped bar portion from downward displacement.

18. The rail anchor as substantially set forth in claim 15, characterized by a relatively upper portion of the channel arms, between which the rear bar section is projected rearwardly, being skewed to dispose their inner surface portions adjacent to their rear edges in more closely converged relation than more forwardly disposed portions thereof to effect inwardly directed resilient frictional pressure by the converged arm surfaces against said bar sides, and by the provision of said clamp arms being formed to provide downwardly directed companion ledge shoulders in the region below the forward portions of the jaw surfaces and inter-spaced above the forward edge portion of the clamp web to restrain undue upward movement of the portion of the bar disposed above and close to said the upper forward surface portion of said web.
